UNITED STATES PATENT OFFICE.

HENRY W. BODENDIECK AND MELVIN T. TIPSORD, OF TAYLORVILLE, ILLINOIS, AS
SIGNORS TO TIP'S TOOL COMPANY INCORPORATED, OF TAYLORVILLE, ILLINOIS,
A CORPORATION OF ILLINOIS.

TIE STICK FOR HANDLING LIVE WIRES.

Application filed March 1, 1926. Serial No. 91,467.

The invention relates to means for tying and untying tie wires on high tension electric lines, to remove or replace, insulators, poles, towers, cross arms, hardware, or other fixtures charged with electric current at voltages dangerous to human life; also for removing kites, kite tails, wires, or other articles, likely to come in contact with high tension lines or appurtenances, and for re-
moving and installing live wire clamps or comealongs etc. and also useful to safely push, pull, raise, or lower live wires at any voltage.

The invention relates also to improved means minimizing the risk of accidental short circuiting of the current, which would almost certainly be fatal to the user of the tie-stick.

The purposes of the invention are: to provide a tie-stick of improved construction adapted, first—to release either terminal of a wire which ties a line wire, or the like, on an insulator or other structure; second—to form the freed terminal part of the tie wire so that it may be engaged and safely manipulated by the tie-stick in the hands of the operator; and third—to provide a pronged twister of improved form, whereby the tie wire may be hooked on the central prong and coiled loosely around the outside prongs of the twister while, and as fast as the tie wire is uncoiled from the line wire or other structure, thus preventing the tie wire from falling, or coming in contact with other wires, machines or structures; to provide a tie-stick adapted to easily and safely open or close switches controlling high tension currents; to provide a tie-stick having a twister head supported by a neck extending a considerable distance upwardly beyond the body to which it is attached at the upper end of the insulating staff, to permit the twister head to carry the coil of the wire above and across the line wire, to permit the prongs of the head to be engaged with, or disengaged from the coil of the tie wire, from either side of the line wire to provide in conjunction with an insulating staff, simple and effective means for "starting" and bending either terminal of a tie wire to form a loop at one end of the tie wire to receive one of the prongs of the twister head in order that the wire may be coiled loosely around the prongs of the head upon proper manipulation of the staff; to provide on the insulating staff of the tie-stick an effective guard against improper use of the

tie-stick; and to provide a tie-stick embodying improved structural details specially adapting it for the purposes stated.

The invention is illustrated in the accompanying drawings, to which reference is hereby made and will now be described and the novel features thereof will be recited in the claims.

Figure 1 is a side elevation of a tie-stick embodying our invention; Fig. 2 is a top view of the same tie-stick; Fig. 3 is a diagram showing in full lines a tie-stick on one side of the live wire and engaging a tie wire, and showing in dotted lines, the changed position of the same tie-stick after it has been shifted to the opposite side of the live wire; Fig. 4 is a fragmentary perspective view showing a tie-stick, and its quadruple hook in operative relation to two high tension line wires and tie wires connected with the respective line wires. Fig. 5 is a diagram illustrating the mode of use of the tie-stick to unwind a tie wire from the live wire; and Fig. 6 is a plan view of a preferred form of tie wire specially adapted for use with the tie-stick.

Similar reference numerals designate similar parts in the several views.

We will now describe the mechanical construction of the tie-stick and some typical modes of using it.

The staff 7 is of wood or other suitable insulating material adapted to withstand the heaviest voltages carried by power transmission lines. The twister is a metal structure comprising a body 8 permanently attached at the upper end of the staff; a relatively long neck 9 of reduced diameter; a head 10, and three tapered prongs 11 integral with the head. The width between the prongs is such as to admit the tie wire 22 freely but is restricted to such extent that the prongs will hold the inserted end of the wire, so that the wire will be coiled loosely around the prongs when upon proper manipulation of the staff, the prongs are caused to follow an approximately circular line of travel in a plane approximately parallel to the plane in which the axis of the staff has at the time, a reciprocating travel. The neck 9 is elongated and reduced in diameter in order that when the head on the tie-stick is raised somewhat above the line wire, the prongs 11 may extend above and across the line wire in such

position that the coiled part of the tie wire carried by the prongs may rest on the line wire to permit retracting of the prongs; and then carrying the tie-stick around to the opposite side of the line wire and inserting the prongs again in the same coil as indicated in Fig. 3, to permit downward movement of the tie wire relative to the line wire.

A quadruple hook 12, shown in detail in Figs. 2 and 4 is secured to the staff by screws 13 and has an upper hook member 15 having a V-shaped notch 16 and beveled edges 18 adapted to engage and hold wires of different sizes; and a lower hook member 14 having a similar notch 17 with similar beveled edges 19. The hook 14 is used to push a member of the tie wire upwardly.

The arched part of the member 14 is adapted to push on line wires, or other relatively large or heavy articles such as the branches of trees, or instruments such as motors, transformers or other machines which it is desired to connect with, or disconnect from the hot wires; and the arched part of the member 15 is adapted to pull on similar articles in a similar manner.

The notched terminal of the member 15 is adapted to pull on tie wires of various sizes, or other small wires, or on twigs, strings or similar light articles which interfere with the work of the operator.

The bevel edges of the members 14 and 15 are adapted to be pressed between the line wire and the terminal of the tie wire which is being operated upon, to bend said terminal outwardly from the periphery of the line wire so that the freed terminal of the tie wire may enter the notch 17, or 16, as the case may be. When the tie wire is in the notch 17, upward or forward movement of the staff 7, on which the hook 12 is secured, will result in further uncoiling of the tie wire 22, (Fig. 4) from the line wire 21. If the free terminal part of the tie wire be engaged in the notch 16, downward or rearward movement of the tie-stick, then on the opposite side of the line wire, will result in partial winding of the tie wire around the line wire; hence the hook as a whole, when applied first on one side of the line wire or other structure, and then on the opposite side of the same line wire or structure, is effective to wind the tie wire around the line wire or structure and to unwind the tie-wire from the same line wire or structure.

Other different uses of the quadruple hook will be apparent to persons skilled in the art and need not be described here.

The hook 12, is called a quadruple hook because it comprises in a single structure, first, an arched element 14, effective to receive and push on an article in the arch, when the tie-stick is moved upwardly or forwardly relative to the operator; second, a notched and beveled element 14^a, effective to start and

push the terminal part of a tie away from the line wire during upward or forward movement of the tie-stick relative to the operator, to unwind a tie wire from a line wire; and also effective to wind the tie wire around the line wire; third, an arched element 15, effective to receive and pull on an article in the arch when the tie-stick is moved downwardly or rearwardly relative to the operator; and fourth, a notched and beveled element 15^a effective to start and pull on the free part of a tie wire and co-acting with the element 14^a to wind the tie wire around the line wire during upward or forward movement of the tie-stick relative to the operator, alternating with downward or rearward movement of the tie-stick relative to the operator.

When linemen are engaged in tying or untying wires on insulators, it is sometimes necessary to jerk, or in a way ram, the tie wire with the tie-stick, and usually in such cases the workman grasps the tie as close to the dangerous end as he deems safe.

If he rams or jerks the wire he is working on, there is always risk that the tie-stick will slip off the wire or out of the loop, with the result that the tie-stick will go free with his force and weight behind it, thereby causing some part of his body to come in contact with the live wire; thus causing his death.

To the best of our knowledge and belief, no means has been hitherto devised and applied to obviate such disastrous mistakes of judgment. We have devised and embodied a scientifically tested guard which will now be described.

The guard 25 consists of a rigid disc of insulating material, such as indurated fibre, or the like, placed on the staff at a safe distance from the metal twister head on the upper end of the staff, and secured by a suitable securing device 26. Said safe distance is determined by actual test in each case and is independent of the individual judgment of the user. This appliance is for the safety of the workman and assures that he will be safe if he always grasps and holds only that part of the staff which is below the disc.

The mode of using the tie-stick to uncoil tie wires from a live wire is indicated diagrammatically in Fig. 5: darts 23 indicate downward travel of the tie-stick in front of the live wire while the tie wire is being coiled around the prongs of the twister head; and darts 24 indicate upward travel of the same tie-stick behind the same line wire. The tie-stick represented by darts 23 pulls downward the front members of the tie wire and darts 24 pull upward the rear members of the same tie wire. At this stage of the operation, the tie-stick will be transferred to the opposite side of the line wire and the prongs will be engaged in the coiled tie wire; then resting on the line wire; and the same operation will

be repeated until the tie wire is completely detached and the detached tie wire will be carried on the prongs of the twister head so that it cannot fall into dangerous position.

5 Having fully described our invention what we claim as new and desire to secure by Letters Patent is:

1. In conjunction with an insulating staff for manipulating live electric wires carrying 10 dangerous voltages; a quadruple hook attached to the insulating staff with which it is usable and comprising in a single structure an upper arch-element adapted to receive and pull on relatively large articles, upon down- 15 ward or rearward movement of said staff; a notched element integral with said upper arch-element and having beveled edges adapted to engage the end of a tie wire and push it outwardly away from the live wire, 20 and adapted also to pull on the live wire and to pull downwardly on any interfering articles during downward or rearward movement of said staff; a lower arch-element adapted to receive and push on the live wire or on other 25 relatively large articles during upward or forward movement of said staff; and a lower notched element having beveled edges adapted to engage on and push outwardly the terminals of tie wires, and also adapted to push 30 upward relatively small articles upon upward or forward movement of said staff.

2. A winding element for tie sticks, comprising a tubular body adapted for attachment on an insulative tie stick; an elongated 35 neck of considerably less diameter than said

body, and adapted to permit the body to take position under the live wire with which it is usable; a rounded head integral with said neck; a relatively short tapered central prong and two longer outside tapered prongs integral 40 with said head and spaced apart from each other to permit free placing of the bent terminal part of a tie wire on said central prong; said outside tapered prongs extending beyond said central prong a sufficient distance 45 to permit coiling of a tie wire held by the central prong, around both of said tapered outside prongs upon a rotative movement of the winding element around the live wire, and permitting free withdrawal of the winding 50 element from the coiled wire, at successive stages of the winding.

3. In conjunction with an insulating staff for manipulating live wires at dangerous voltages; a quadruple hook permanently attached to said insulating staff parallel thereto and having arched elements, one at each end, capable of push-and-pull action responsive to lengthwise movements of said staff, and notched elements integral with the respective 55 arched elements each one adapted for pushing in one direction and pulling in the opposite direction responsive to the lengthwise movements of said staff.

In witness whereof we have hereunto 60 signed our names at Taylorville, Christian County, Illinois, this 24th day of February 1926.

HENRY W. BODENDIECK.
MELVIN T. TIPSORD.
